(57) **CLAIM**

The ornamental design for a front face of a vehicle wheel, as shown and described.

DESCRIPTION

FIG. 1 is a front view of a front face of a vehicle wheel showing my new design;

FIG. 2 is a front and right side perspective view of the front face of the wheel shown in FIG. 1; and,

FIG. 3 is a different perspective view of the front face of the wheel shown in FIG. 1.

Throughout the various figures of the drawings, certain views are not provided. The omission of a particular view is intended to convey that the element(s) depicted is/are plain and unornamented in that omitted view, or that the particular ornamental appearance in that view is simply not claimed. Where included, broken lines showing environment or structure are for illustrative purposes only and form no part of the claimed design.
